(57) **CLAIM**

The ornamental design for a pizza maker, as shown and described.

DESCRIPTION

FIG. 1 is a front right perspective view of a pizza maker showing my design;

FIG. 2 is a left side view of the pizza maker shown in FIG. 1;

FIG. 3 is a right side view of the pizza maker shown in FIG. 1;

FIG. 4 is a front view of the pizza maker shown in FIG. 1; FIG. 5 is a rear view of the pizza maker shown in FIG. 1; FIG. 6 is a top view of the pizza maker shown in FIG. 1; FIG. 7 is a bottom view of the pizza maker shown in FIG. 1; and,

FIG. 8 is a rear perspective view of the pizza maker shown in FIG. 1.

The broken lines represent portions of the pizza maker that form no part of the claimed design.

1 Claim, 8 Drawing Sheets
